UNITED STATES PATENT OFFICE.

NATHAN CARLETON PHILLIPS, OF GLOUCESTER, MASSACHUSETTS, ASSIGNOR TO RUSSIA CEMENT COMPANY, OF GLOUCESTER, MASSACHUSETTS, A CORPORATION OF MASSACHUSETTS.

INK PACKAGE.

Application filed April 12, 1927. Serial No. 183,077.

This invention relates to an ink bottle adapted for use as an ink well from which ink may be taken by a pen inserted in the neck of the bottle, the storage space in the 5 bottle being of uniform cross-sectional area or diameter, from the bottom to the top or breast of the bottle body, so that the bottom of said space is not larger than the top.

A bottle thus formed is desirable because 10 it is adapted to maintain a charge of ink in compact form, without enlargement of the lower portion of the charge. Such bottle is liable, however, to be easily tipped over, this liability being an objection to the use 15 on a desk or table of a bottle thus characterized.

The object of the invention is to provide 20 means for stably supporting a bottle of the general form above indicated, and at the same time, protect the bottle body while in 25 storage and shipment, and provide a package having an external surface of more attractive form than that of the bottle itself.

I accomplish these results by providing 30 the bottle with a jacket characterized as hereinafter described, the bottle and jacket constituting a new and improved ink package.

Of the accompanying drawings forming a 35 part of this specification,—

Figure 1 is a perspective view of an ink package embodying the invention, the bottle body being shown by dotted lines.

Figures 2 and 3 are perspective views, 40 showing separately the parts of the jacket.

Figure 4 is a section on line 4—4 of Figure 1.

The same reference characters indicate 45 the same parts in all of the figures.

12 designates the body, 13 the bottom, 14 the breast, and 15 the neck, of an ink bottle adapted to be used on a desk or table as an ink well, into which a pen may be dipped.

The body 12 is of substantially uniform 50 cross-sectional area from the bottom to the breast, or from end to end, so that the bottle is not larger at its lower than at its upper end. The external surface of the body may be either cylindrical or square. There is nothing new in a bottle characterized as above stated. It is obvious that the breast may be domed instead of flat.

In carrying out my invention, I combine with the bottle, a confining jacket composed

of a body formed to enclose the body of the 55 bottle, and having an open mouth, and a cover closing said mouth and provided with an orifice through which the bottle neck projects, these parts being made of suitable sheet material, preferably sheet metal. 60

The jacket body includes a bottom 16, having a considerably greater area than the bottom of the bottle, and an open-mouthed enclosing wall 17, upstanding from the bottom and inclined inwardly therefrom, so 65 that the wall is tapering and its mouth is formed to bear on the upper end of the bottle body, and confine the bottle against lateral movement in the jacket.

The cover, designated by 18, has a flange 70 19 overlapping the upper end portion of the wall 17. The cover bears on the breast 14, to confine the bottle against vertical movement in the jacket. The cover has an orifice 20, through which the neck 15 projects. I 75 prefer to rigidly secure the cover flange 19 to the jacket body, so that the cover cannot be easily removed, and cannot be removed without distortion or defacement. To this end, the flange may either have a very close 80 driving fit on the upper end portion of the jacket body, or may be soldered, or otherwise fixed thereto. The body 17 is preferably provided with a bead 21, on which the lower edge of the cover flange abuts. 85

The external surface of the wall 17 is preferably substantially square in cross section, and provided with truncated corners, as indicated by Figures 1 and 2, the cover flange 19 being similarly formed. 90

The jacket body enlarged at its bottom and tapering inwardly to its top, provides a stable support for the bottle, obviating liability of the accidental overturning of the latter when in use, and protects the bottle 95 body from injury when in storage and shipment.

The tapering form of the jacket and the general design thereof, shown by Figures 1 and 3, impart a novel and attractive form to 100 the package as a whole. The flat sides of the wall 17 are adapted to be decorated by lithography, or otherwise, to heighten the attractive appearance of the package.

I claim:

An article of the character described comprising a bottle, having an upwardly extending screw threaded neck, and a confin-

ing jacket of sheet material completely enclosing the body of the bottle and through which the neck projects, said jacket comprising a bottom of greater area than the 5 bottom of the bottle, an open-mouthed enclosing wall extending upward from the bottom and inclined inwardly therefrom in- to close engagement with the bottle to prevent relative turning movement between the 10 bottle and the jacket when applying or removing an internally threaded cap to or

from the threaded neck and a cover bearing on the top of the bottle about the neck and having a depending flange surrounding and secured to the portion of the jacket wall that contacts with the bottle to maintain the lateral engagement between the jacket and bottle and clamp the bottle vertically against the bottom of the jacket. 15

In testimony whereof I have affixed my 20 signature.

NATHAN CARLETON PHILLIPS.
